UNITED STATES PATENT OFFICE.

ESTLE DEE PLYLEY, OF DETROIT, MICHIGAN.

AUTOMATIC STREET INDICATOR FOR RAILWAY CARS.

Application filed September 1, 1922. Serial No. 585,751.

To all whom it may concern:

Be it known that I, ESTLE DEE PLYLEY, a citizen of the United States of America, residing at Detroit, in the county of Wayne 5 and State of Michigan, have invented certain new and useful Improvements in Automatic Street Indicators for Railway Cars, of which the following is a specification, reference being had therein to the accompanying drawings.

The invention relates to automatic indicators more particularly designed for use on street railway cars for indicating the name of the approaching street. It is the object 15 of the invention to obtain a construction which is controlled by means located in the over-head structure so as to avoid the necessity of any obstruction in the street. It is a further object to obtain a construction 20 which may be easily adjusted to suit re-routing of the cars and which may also be quickly readjusted upon the completion of the trip. The invention therefore consists in various features of construction as herein- 25 after set forth.

In the drawings:

Figure 1 is a diagram indicating a street car and over-head trolley system, to which my improvements are applied;

Figure 2 is a plan view of the over-head structure and trolley arm;

Figure 3 is a perspective view of the indicator casing;

Figure 4 is a perspective view of one of 35 the combined indicator and advertising cards;

Figures 5 and 6 are respectively a horizontal section and vertical longitudinal section through the indicator housing the latter figure being taken on the line 6-6 of Figure 5;

Figure 7 is a cross-section on line 7-7 of Figure 5;

Figure 8 is a cross-section on line 8-8 of Figure 6;

Figure 9 is a sectional perspective view 45 showing a portion of the housing and actuating ratchets for the indicator cards;

Figure 10 is a perspective view of the end clamping plate; and

Figures 11 and 11^a are cross-sections in 50 transverse planes through the follower.

My improved construction is applicable to any type of railway car in which there is an over-head construction such as formed by the posts A and cross wires B which suspend the trolley wire C. The trips or actuating

devices for the indicator are secured to depend from the cross wires B, as indicated at D, and they are so arranged as to be in the path of an electric switch E mounted upon the trolley pole F. This switch is double acting, being thrown in one direction to close an electric circuit by the actuation of one of the trips D and being thrown in the opposite direction to open the circuit by the actuation of a succeeding trip D'. Thus a sufficient time interval is given between the successive actuations of these trips to permit the operation of the indicator mechanism.

The indicator comprises a casing or housing G, which is divided by the horizontal partition H into an upper and lower compartment. At one end of this housing there is arranged a transparent panel I, preferably a lens, through which the registering indicator card may be observed in magnified form. These indicator cards J preferably have in the central portion J' thereof the name or number of the street and upon opposite sides of the central portion panels J² 70 and J³ containing advertising matter. As the cards are successively displayed, it is obvious that a large number of advertising displays may be exhibited and the revenue derived therefrom will be sufficient for the 75 installation and the maintenance of the indicator system.

The cards J are arranged in series and originally placed in the upper compartment with a follower K at the rear end of the 80 series. In the lower compartment there is also a follower block K' and, as will be presently described, these blocks K and K' are actuated step by step in opposite directions, the one to advance and successively 85 drop the cards of the series and the other to provide for the reception of the used cards.

The actuating means for the followers 90 preferably comprises a solenoid or electric magnet L at the rear end of the housing, which, when energized, actuates the core L' against the tension of a spring L². Secured to the core L' is a frame M connected to the ratchet bars M', M², M³, M⁴, on opposite sides of the housing and centrally of the upper and lower compartments thereof. At the top of the compartments are the stationary ratchet bars N and N' having their teeth oppositely facing from those of the 95 bars M', M², etc. O are dogs on the followers K and K' which engage the teeth of 100

105

110

the ratchet bars M' , M^2 , etc., the arrangement being such that when the ratchet bars M' , M^2 , etc., are actuated by the energized solenoid, they will advance the follower K 5 in a direction towards the lens I and will advance the follower K' in the reverse direction. Also, when the solenoid is de-energized and the frame M returned by the spring L^2 , the stationary ratchet bars N and N' will hold both series of cards from reverse movement.

For the successive display of the cards it is necessary at each step to remove a card from the upper series and to introduce the 15 same into the lower series. This is accomplished by providing an aperture P in the partition H through which the end card of the upper series is permitted to drop when sufficiently advanced. A plate P' is yieldably pressed by springs P^2 against the cards in the lower series slightly overlapping the cards of the upper series and this plate is moved forward by the ratchet bars M^3 simultaneously with the forward advancement of 20 the cards in the upper series. Thus, upon each forward actuation of the upper series one card will drop from the end into the lower series.

To reset the indicator after the car has 30 completed its route and all of the cards in the upper series have been transferred to the lower, provision is made for a retransfer of said cards. This comprises trays arranged respectively in the upper and lower 35 compartment over which the cards are fed and which may be used for lifting the whole series from one compartment and transferring it to the other. The end of the housing, which has the lens I , is preferably in the form of a hinged door I' and this may 40 be opened and turned back to provide access to the two compartments. It is also necessary to adjust the followers, moving that of the upper compartment backward in the 45 casing and that in the lower compartment forward. For such purpose I have provided externally operable means for retracting the dogs O on the followers K and K' and for moving the said followers longitudinally of the case. Such means comprises 50 specifically the rod Q , which extends through the slot R in the casing and into engagement with the follower, being connected to a bell crank lever Q' having three arms connected 55 by the rods S with the dogs O . With this arrangement by pulling upon the rod Q , all of the dogs are released from the ratchet bars, after which the rod Q may be moved laterally, moving the follower with it to the 60 desired position of adjustment.

In use, the cards are arranged in series corresponding in name or number to the street to be indicated and in the same order. These cards are then placed in the tray 65 which is inserted in the upper compart-

ment, the follower K having previously been adjusted rearward in the manner previously described. When the car is traveling, the electric switch E is alternately opened and closed by engagement with successive trips D and D' , this occurring after each indicated street has been passed. When the switch is operated to close the circuit, the solenoid actuating the ratchet bars simultaneously will move the follower 75 K' one step rearward and will engage another notch of each of the ratchet bars M' and M^2 with the dogs O of the follower K . Also the plate P' actuated by the springs P^2 will move the lower series of cards rearward. Upon the opening of the switch the solenoid is de-energized, which permits the spring L^2 to actuate the ratchet bars in the reverse direction. The ratchet bars M' and M^2 will thus move forward the follower 80 K , which will advance the entire series of upper cards, the end card of said series moving the plate P' forward against the action of the springs P^2 and finally dropping through the aperture P to the lower series. 90

What I claim as my invention is:

1. In a street indicator, the combination with a holder for a series of cards, of a follower slidably arranged in said holder, stationary ratchet bars having teeth facing 95 in one direction, movable ratchet bars having oppositely facing teeth, dogs upon said follower engaging the respective ratchet bars, means for reciprocating said movable ratchet bars to advance said follower and the series of cards step by step and means operating after each advancement for removing a card from said holder.

2. In a street indicator, the combination of a holder having compartments for two 105 series of cards, followers slidably arranged in each of said compartments, dogs upon said followers, a reciprocating member, ratchet bars on said member having teeth facing in opposite directions for engaging the dogs on the respective followers, means for reciprocating said ratchet bars to successively move the respective followers and series of cards in opposite directions, means operating after each reciprocation for transferring a card from one series to the other 110 series and means normally preventing the return movement of said followers.

3. In a street indicator, the combination of a holder having compartments for two 115 series of cards, followers slidably arranged in each of said compartments, a reciprocable member provided with ratchet bars having teeth facing in opposite directions, dogs upon the followers engaging said ratchet bars, means for advancing said reciprocable member to move one of said followers in one direction to advance one series of cards, means for transferring a card from said 120 series to the other series, means for subse-

quently retracting said reciprocable member to move the other follower in the opposite direction, and means normally preventing the return movement of the respective followers.

4. In a street indicator, the combination with a holder having a slotted horizontal partition therein forming upper and lower compartments for two series of cards, followers slidably arranged in each of said compartments, a reciprocable member provided with ratchet bars having teeth facing in opposite directions, dogs upon the follower in the upper compartment engaging the ratchet bars with teeth facing in one direction, dogs upon the follower in the lower compartment engaging the ratchet bars having oppositely facing teeth, means for advancing the reciprocable member to advance the upper follower, means for retracting said reciprocable member to move the lower follower in the opposite direction, means for normally preventing the return movement of each of said followers, and a yieldably pressed plate at the front end of said lower compartment actuated by the advancement of said reciprocable member to allow a card in the upper series to be transferred to said lower series through the slot in said partition.

5. A street indicator comprising a holder having upper and lower compartments for two series of indicating cards, ratchet toothed bars for advancing the cards of said series in opposite directions, an electro-magnet for reciprocating said ratchet bars, the forward movement of said magnet advancing one of said series, and the opposite movement actuating the other of said series, and means operating upon each advancement of said upper series for dropping a card therefrom to the lower series.

6. A street indicator comprising a holder having upper and lower compartments for two series of indicating cards, ratchet toothed bars for advancing the cards of said series in opposite directions, an electro-magnet for reciprocating said ratchet

bars, the forward movement thereof advancing the upper series, and the rearward movement actuating the lower series, a plate normally engaging the end card of the lower series and arranged to be laterally displaced by the forward movement of said ratchet bars, a partition between said upper and lower compartments having an aperture therethrough registering with the upper end card when in advanced position through which said card drops to the lower series, and resilient means for returning said plate to normal position to move the cards in said lower series upon the rearward movement of said ratchet bars.

7. In a street indicator, the combination with a holder having compartments for two series of cards, a partition between said compartments having an aperture therein, means for advancing said series step by step in opposite directions including a plate normally engaging the end card of the lower series and arranged to be laterally displaced by the movement of the upper series whereby a card from said upper series is transferred through said aperture to said lower series, and resilient means for returning said plate to normal position and thereby moving said lower series of cards.

8. In a street indicator, the combination with a holder having a slotted horizontal partition therein forming upper and lower compartments for two series of cards, followers slidably arranged in each of said compartments, a reciprocable member adapted to successively advance the followers in said upper and lower compartments, the upper series of cards being moved forwardly by the advancement of said upper follower, and a yieldably pressed plate at the front end of said lower compartment actuated by the advancement of the upper series of cards to allow the end card thereof to be transferred to said lower series through the slot in said partition.

In testimony whereof I affix my signature.

ESTLE DEE PLYLEY.
